UNITED STATES PATENT OFFICE.

FRANK W. WHITCHER, OF BOSTON, MASSACHUSETTS.

DESIGN FOR AN INCISING-DIE.

SPECIFICATION forming part of Design No. 29,824, dated December 20, 1898.

Application filed November 3, 1898. Serial No. 695,402. Term of patent 14 years.

To all whom it may concern:

Be it known that I, FRANK W. WHITCHER, a citizen of the United States, residing at Boston, in the county of Suffolk and State of Massachusetts, have invented and produced a new and original Design for Incising-Dies, of which the following is a specification, reference being had therein to the accompanying drawing.

10. The accompanying drawing is a perspective view, on an enlarged scale, showing my design.

15. The leading or material features of my design for a die for making simple incisions in leather or other material without the removal of any portion of the latter comprise the

horseshoe conformation of the cutting edge at 1, the corresponding cross-sectional shape of the body 2 of the die, the barrel-like contour of the said body, the longitudinal tapering faces 3 3, and the opening 4 between the said faces.

20. What I claim as new, and desire to secure by Letters Patent, is—

25. The design for an incising-die, as herein shown and described.

In testimony whereof I affix my signature in presence of two witnesses.

FRANK W. WHITCHER.

Witnesses:

CHAS. F. RANDALL,
LEPINE HALL RICE.
